ABSTRACT

Novel ureas and thioureas of the formula

where X is oxygen or sulfur, R₁ and R₂ are alkyl radicals of not more than four carbon atoms, R₃ is alkyl of not more than 12 carbon atoms, alkenyl of not more than 12 carbon atoms, cycloalkenyl of six through eight carbon atoms, haloalkyl of not more than 12 carbon atoms and with not more than three halogen atoms therein on the one and two carbon atoms, halophenyl of not more than five halogen atoms, haloalkylphenyl of not more than three haloalkyls having not more than four carbon atoms and not more than three halogen atoms therein, with the provision that the double bond in said alkenyl and cycloalkenyl are not in the 1-position.

These compounds are useful as herbicides.

BENZOTHIAZOLINYLIDENE SUBSTITUTED UREAS

BENZOTHIAZOLINYLIDENE SUBSTITUTED THIOUREAS

This invention relates to new ureas and thioureas. These new compounds are useful in controlling the growth of plants.

The new compounds of this invention are of the formula

where X is oxygen or sulfur, R₁ and R₂ are alkyl radicals of not more than four carbon atoms, R₃ is alkyl of not more than 12 carbon atoms, alkenyl of not more than 12 carbon atoms, cycloalkenyl of six through eight carbon atoms, haloalkyl of not more than 12 carbon atoms and with not more than three halogen atoms therein on the 1 (or α) and 2 (or β) carbon atoms, halophenyl of not more than five halogen atoms, haloalkylphenyl of not more than three haloalkyls having not more than four carbon atoms and not more than three halogen atoms therein, with the proviso that the double bond in said alkenyl and cycloalkenyl are not in the 1-position.

Preferred compounds of this invention are those wherein X is sulfur or wherein R₃ is alkyl or alkenyl and wherein X is sulfur and R₃ is alkyl simultaneously. Other preferred embodiments are halophenyl radicals which have a maximum of three halogens on the phenyl ring.

The alkyl radicals represented by R₁ and R₂ can be straight or branched, primary, secondary or tertiary. For example, R₁ and R₂ can each be methyl, ethyl, propyl, isopropyl, n-butyl, sec. butyl and tert. butyl.

The alkyl radicals represented by R₃ can likewise be straight or branched, primary, secondary or tertiary. Examples are methyl, propyl, isopropyl, n-butyl, sec. butyl, isobutyl and tert. butyl, n-hexyl, isononyl, n-dodecyl and isododecyl.

Examples of alkenyl radicals represented by R₃ are 2-propenyl, 2-butenyl, 2-isobut enyl, 2-hexenyl, 3-nonenyl, 2-dodecenyl.

Examples of cycloalkenyl radicals represented by R₃ are 2-cyclohexenyl, 3-cyclohexenyl and 2-cyclooctenyl.

Examples of haloalkyl radicals represented by R₃ are chloromethyl; trifluoromethyl; 2-bromoethyl; iodomethyl and 2,2,2-trifluoromethyl.

Examples of halophenyl radicals represented by R₃ are 2-chlorophenyl; 2-fluorophenyl; 4-bromophenyl; 2-iodophenyl; 2,4-difluorophenyl and 2,4,6-trichlorophenyl.

Examples of haloalkylphenyl radicals represented by R₃ are 2-trifluoromethylphenyl; 4-bromomethylphenyl; 4-iodomethylphenyl; 3-chloromethylphenyl and 3,5-di(trifluoromethyl)phenyl.

Illustrative examples of the compounds of this invention are:

- 1-(3,6-dimethyl-2-benzothiazolinylidene)-3-methylurea
- 1-(3-methyl,6-tert, butyl-2-benzothiazolinylidene)-3-methylurea
- 1-(3,6-dimethyl-2-benzothiazolinylidene)-3-iso-dodecylurea
- 1-(3,6-dimethyl-2-benzothiazolinylidene)-3-(2-isobut enyl)urea
- 1-(3,6-dimethyl-2-benzothiazolinylidene)-3-(2-dodec enyl)urea
- 1-(3,6-dimethyl-2-benzothiazolinylidene)-3-(2-cyclohex enyl)urea
- 1-(3,6-dimethyl-2-benzothiazolinylidene)-3-trifluoromethylurea
- 1-(3,6-dimethyl-2-benzothiazolinylidene)-3-(2-fluorophen yl)urea
- 1-(3,6-dimethyl-2-benzothiazolinylidene)-3-(2,4-dibromophen yl)urea
- 1-(3,6-dimethyl-2-benzothiazolinylidene)-3-(3-chloromethylphen yl)urea

- 1-(3,6-dimethyl-2-benzothiazolinylidene)-3-methyl-2-thiourea
- 1-(3-methyl,6-tert, butyl-2-benzothiazolinylidene)-3-methyl-2-thiourea
- 1-(3,6-dimethyl-2-benzothiazolinylidene)-3-isopropyl-2-thiourea
- 1-(3,6-dimethyl-2-benzothiazolinylidene)-3-(2-isobut enyl)-2-thiourea
- 1-(3,6-dimethyl-2-benzothiazolinylidene)-3-(2-cyclohex enyl)-2-thiourea
- 1-(3,6-dimethyl-2-benzothiazolinylidene)-3-chloromethylurea
- 1-(3,6-dimethyl-2-benzothiazolinylidene)-3-(2,2,2-trifluoroethyl)urea
- 1-(3,6-dimethyl-2-benzothiazolinylidene)-3-(2-fluorophen yl)-2-thiourea
- 1-(3,6-dimethyl-2-benzothiazolinylidene)-3-(2,4-dibromophen yl)-2-thiourea

The compounds of this invention in general can be prepared by reacting the 3,6-dialkyl-2-benzothiazolinylimine with the isocyanate or isothiocyanate corresponding to the structure desired as product although the iodoalkyl containing compounds are more suitably prepared by preparation of a corresponding different haloalkyl and then displacing the halo thereof with NaI in acetone at room temperature (i.e. about 20° C) and pressure (i.e. about 15 psi.).

The reaction will be made clear by the following detailed examples.

EXAMPLE I

About 0.05 mole or 8.7 g. of 3,6-dimethyl-2-benzothiazolinylimine was dissolved in about 50 ml. of ether and was placed in a four-necked flask equipped with a thermometer, stirrer, condenser (using tap water) and a dropping funnel. About 0.05 mole or 3.7 g. of methylisothiocyanate was added dropwise to the solution in the flask. The reaction was noted to be slightly exothermic. The mixture was allowed to stand overnight and filtered. The yellow needles were recrystallized from about 300 ml. of acetonitrile and dried at about 100° C at 0.3 mm. Hg. An off-white powder melting at 205.5°–217.5° C. was obtained. Elemental analysis was as follows:

	C ₁₁ H ₁₃ N ₃ S ₂	%C	%H	%N
Calculated:		52.55	5.21	16.71
Found:		52.53	5.27	16.81

Nuclear magnetic resonance (NMR) spectral analysis confirmed the product 1-(3,6-dimethyl-2-benzothiazolinylidene)-3-methyl-2-thiourea.

EXAMPLE II

Using similar equipment as that in Example I, 0.05 mole or 8.7 g. of 3,6-dimethyl-2-benzothiazolinylimine was dissolved in about 150 ml. of ether and placed in the flask. About 0.05 mole or 9.4 g. of 3,4-dichlorophenylisocyanate dissolved in about 60 ml. of ether was added dropwise to the flask. The reaction was exothermic and solid product formed immediately. The solid was filtered and recrystallized from dimethylformamide. Recrystallized product dried at about 100° C at 0.2 mm. Hg. had a melting point of 216°–218° C. Elemental analysis was as follows:

	C ₁₆ H ₁₃ Cl ₂ N ₃ OS	%C	%H	%N
Calculated:		52.47	3.58	11.47
Found:		52.53	3.62	11.61

NMR spectral analysis confirmed the expected product 1-(3,4-dichlorophenyl-(3,6-dimethyl-2-benzothiazolinylidene)urea).

As aforementioned, the compounds of this invention are useful in controlling the growth of plants. This utility will now be discussed and exemplified.

The term "herbicide" as used herein and in the appended claims means materials which control the growth of plants

either (1) all plants in a given locus or (2) selectively the growth of one or more plant species in the presence of other plants. In like manner, "herbical" is used to identify the overall as well as the selective control activity of the compositions of this invention.

The term "plant" as used herein and in the appended claims is inclusive of dormant seeds, germinant seeds, germinative seeds, emerging seedlings and established woody and herbaceous vegetation including the roots and above-ground portions.

The term "control" as used herein and in the appended claims is inclusive of the actions of (1) killing, (2) inhibiting growth, reproduction or proliferation, and (3) removing, destroying or otherwise diminishing the occurrence and activity of plants and is applicable to any of the stated actions, or any combination thereof.

The term "herbical formulation or composition" as used herein means at least one compound of this invention in combination with an adjuvant.

EXAMPLE III

The pre-emergent herbical activity of the active ingredients of this invention is demonstrated as follows: A good grade of top soil is placed in aluminum pans and compacted to a depth of three-eights to one-half inch from the top of each pan. A pre-determined number of seeds of the test plant species are placed on top of the soil in the pans. The seeds are covered with a three-eighth inch layer of soil and the pan leveled. The active ingredient is applied by spraying it on the surface of the soil as a herbical formulation containing a sufficient amount of active ingredient to obtain the desired rate of active ingredient per acre.

The seed-containing pans are placed on a sand bench and maintained under ordinary conditions of sunlight and watering. The plants are observed at the end of approximately 14 days and the results recorded. The herbical activity index is based on the average percent control of each seed lot. The herbical activity index is converted to a relative numerical scale for the sake of brevity and simplicity in the table.

The pre-emergent herbical activity index used is defined as follows:

Average Percent Control	Numerical Scale	
0 to 25	0	45
26 to 50	1	
51 to 75	2	
76 to 100	3	

In Table I, below, the dosage rate, the spectrum of plant seeds treated, and the results of tests carried out according to the above procedure are indicated for several of the compounds of this invention.

TABLE I

Compound	Dosage, lb./acre	Canada thistle	Cockle-bur	Velvet leaf	Morning glory	Lamb's-quarter	Smart-weed	Nut-sedge	Quack-grass	Johnson grass	Downy brome	Barnyard grass
A	5	0	0	0	2	0	0	2	1	1	0	0
B	5	1	0	0	0	0	0	1	0	1	0	2
C	5	0	0	0	0	0	2	3	0	0	0	1

A = 1-(3,6-dimethyl-2-benzothiazolinylidene)-3-methyl-2-thiourea

B = 1-(3,4-dichlorophenyl)-3-(3,6-dimethyl-2-benzothiazolinylidene)urea

C = 1-methyl-3-(3,6-dimethyl-2-benzothiazolinylidene)urea

The active ingredients herein defined are suitable for both pre-emergent and post-emergent plant application. That is, they are effective in controlling the growth of germinant seeds, emerging seedlings and established vegetation by exposing the seeds emerging seedlings, or the roots or above-ground portions to the action of an effective amount of one or more of these herbicidally active compounds; however, the best results are usually obtained in a pre-emergent application. Such constitutes a preferred embodiment of the utility of these compounds.

70

In foliar treatment of the modification of vegetative growth, the active ingredients are applied in amounts from about 1.0 to about 50 or more pounds per acre, preferably about 0.1 to 15 pounds per acre in foliar treatments. In soil applications, it

5 is desirable that the active ingredients be distributed to a depth of at least 0.2 inches. In pre-emergence herbical applications the active ingredients are usually applied in amounts from about 0.1 to 25 pounds per acre but preferably from about 1.0 to 10 pounds per acre. It is believed that one skilled in the art can readily determine from the teachings of this specification, including examples, the procedure for any particular desired application.

In using the compounds of this invention, the active ingredients can be used along or in combination with a material referred to in the art as an adjuvant in liquid or solid form. The usual purpose of adjuvants is to facilitate application of the herbical composition and to obtain the desired dosage rate.

15 Herbical formulations are prepared by admixing the active ingredient with one or more adjuvant which includes diluents, extenders, carriers and conditioning agents to provide compositions in the form of finely-divided particulate solids, granules, pellets, solutions, dispersions or emulsions. Thus, the active ingredient can be used with an adjuvant such as a finely-

20 divided particulate solids, granules, pellets, solutions, dispersions or emulsions. Thus, the active ingredient can be used with an adjuvant such as a finely-divided particulate solid, a liquid of organic origin, water, a wetting agent, dispersing agent, an emulsifying agent or any suitable combination of these.

25 Suitable adjuvants of the foregoing types are not here defined in detail as to composition, particle size, relative amounts etc. since they are well known in the art.

In general, the active ingredients may be formulated with the active ingredient in minor or major proportions in accordance with the table below:

Type of Formulation	Concentration of Active Ingredient
1. Granules of relatively large particle size	5 to 50%
2. Powdery dusts	2 to 90%
3. Wettable powders	2 to 90%
4. Emulsifiable concentrates	5 to 95%
5. Solutions	.01 to 95%
6. One of the less common types of formulations depending on the desired mode of application	.01 to 95%

30 In addition to adjuvants the compounds of this invention can be used in combination with fertilizers and/or other pesticides such as insecticides, fungicides, nematocides, and/or other phytotoxicants inclusive of herbicides, and the like.

Having now described the invention, many ramifications and modified embodiments will readily occur to those skilled in the art. In so far as such variations do not depart from the spirit and scope of the invention described in this application, they are intended to be embraced by the appended claims in their broadest construction.

65 What is claimed is:

1. A compound of the formula

where X is oxygen or sulfur, R₁ and R₂ are alkyl radicals of not more than four carbon atoms, R₃ is alkyl of not more than 12 carbon atoms, alkenyl of not more than 12 carbon atoms, cycloalkenyl of six through eight carbon atoms, haloalkyl of not more than 12 carbon atoms and with not more than three halogen atoms therein on the one and two carbon atoms, halophenyl of not more than five halogen atoms, haloalkylphenyl of not more than three haloalkyls having not more than 4 carbon atoms and not more than three halogen atoms therein, with the proviso that the double bond in said alkenyl and cycloalkenyl are not in the 1-position.

2. A compound according to claim 1 wherein X is sulfur.
3. A compound according to claim 1 wherein X is oxygen.
4. A compound according to claim 1 wherein R₃ is alkyl.
5. A compound according to claim 1 wherein R₃ is alkenyl.
6. A compound according to claim 1 wherein R₃ is halophenyl with up to three halogens therein.

7. A compound according to claim 2 wherein R₃ is alkenyl.
8. A compound according to claim 2 wherein R₃ is cycloalkenyl.
9. A compound according to claim 2 wherein R₃ is halophenyl.
10. A compound according to claim 3 wherein R₃ is alkenyl.
11. A compound according to claim 3 wherein R₃ is cycloalkenyl.
12. A compound according to claim 3 wherein R₃ is halophenyl.
13. A compound according to claim 1 which is 1-(3,6-dimethyl-2-benzothiazolinylidene)-3-methyl-2-thiourea.
14. A compound according to claim 1 which is 1-(3,4-dichlorophenyl)-3-(3,6-dimethyl-2-benzothiazolinylidene)urea.
15. A compound according to claim 1 which is 1-methyl-3-(3,6-dimethyl-2-benzothiazolinylidene)urea.
